United States Patent Office.

WILLIAM JOHNSTON, OF HAVELOCK, PENNSYLVANIA.

Letters Patent No. 94,607, dated September 7, 1869.

IMPROVED RAILWAY-RAIL JOINT.

The Schedule referred to in these Letters Patent and making part of the same.

To all whom it may concern:

Be it known that I, WILLIAM JOHNSTON, of Havelock, in the county of Washington, and State of Pennsylvania, have invented a new and useful Improvement in Railroad-Rails and Joints; and I do hereby declare that the following is a full, clear, and exact description thereof, reference being had to the accompanying drawings, making a part of this specification, and to the letters of reference marked thereon.

The nature of my invention consists in connecting the joints of railroad-rails with a steel cap, in such a manner as to hold said joints securely without rattling, present a smooth, continuous surface to the wheels, and prevent flattening of the ends of the rails; also in furnishing a means whereby old rails, the ends of which have become flattened, may be used again, by slightly altering them.

To enable those skilled in the art to which my invention appertains to make and use the same, I will proceed to describe its construction and operation.

In the drawings—

A, A' represent two ordinary railroad-rails, and
B, a steel cap, the outside of which corresponds with
the form of the rails.

The ends of the rails have tongues *a* formed on
them, by cutting away a portion of the top, and the

cap B is formed with a groove, *b*, which fits said
tongues when the ends of the rails are together.

The cap B is secured to the rails by bolts *c* passing
transversely through them and held by nuts.

The cap and rails are secured to the ties by spikes
d passing through their flanges and into the ties.

The holes in the rails through which the bolts and
spikes pass, are elongated, so as to allow for expan-
sion and contraction of the rails.

When the ends of the rails are placed together and
the cap secured in place, the joints are held securely,
and present a smooth, continuous surface to the wheels.

When old rails have become flattened at the ends,
by constant use, they may be cut away at the ends,
so as to form tongues, as shown at *a*, and may be used
in connection with the caps B.

Having thus described my invention,

What I claim as new, and desire to secure by Let-
ters Patent, is—

The steel cap B, in combination with the rails A
A', when constructed and arranged as herein shown
and described.

WM. JOHNSTON.
